UNITED STATES PATENT OFFICE.

JOHN L. DAWES, OF PITTSBURGH, PENNSYLVANIA; ELIZABETH McCOMBS DAWES
EXECUTRIX OF SAID JOHN L. DAWES, DECEASED.

DESIGN FOR AN ADVERTISING SIGN.

Application filed April 24, 1923. Serial No. 5,933. Term of patent 7 years.

To all whom it may concern:

Be it known that I, JOHN L. DAWES, a citizen of the United States, and resident of Pittsburgh, Allegheny County, Pennsylvania, have invented a new, original, and ornamental Design for Advertising Sign, of which the following is a specification, reference being had to the accompanying drawings, forming part thereof, in which—vertising sign showing my new design; and

Figure 2 is a side elevation of the same.

I claim:

The ornamental design for an advertising sign, substantially as shown.

In testimony whereof I have hereunto set my hand.

JOHN L. DAWES.
